UNITED STATES PATENT OFFICE.

WILLIAM LEONHARDT, OF BALTIMORE, MARYLAND.

DUMPING-WAGON.

SPECIFICATION forming part of Letters Patent No. 607,249, dated July 12, 1898.

Application filed June 4, 1897. Serial No. 639,425. (No model.)

To all whom it may concern:

Be it known that I, WILLIAM LEONHARDT, of the city of Baltimore and State of Maryland, have invented certain Improvements in 5 Dumping-Wagons, of which the following is a specification.

In the description of the said invention which follows reference is made to the accompanying drawings, forming a part hereof, and 10 in which—

Figure 1 is an exterior side view of the improved dumping-wagon. Figs. 2, 3, 4, 5, and 6 are enlarged details of the invention. Fig. 7 illustrates a modification in a part of the 15 invention.

Referring now to the drawings, A is the body of the wagon, and B and C are respectively the front and rear wheels.

D D are sills supported by any suitable 20 mechanism from the front axle E. These sills are of such length as to support the body in a horizontal position.

F F are plates bolted to the inner sides of 25 the sills D, with their overhanging portions inclined downward. Their lower ends are enlarged, as shown particularly in Fig. 5, and through the enlarged ends is passed the rear axle G, which at this place is turned to a cylindrical shape. The holes a in the plates F 30 are elongated vertically to give the axle a limited vertical movement independently of the body and the sills.

The rear end of the body A is supported by 35 springs H, secured to the axle G, and is not intended to bear on the sills. The springs H are therefore made strong enough to sustain the body when loaded in the position shown in dotted lines in Fig. 2, the lowering of the body to contact with the sills occurring only 40 when the wagon is jolted by passing over rough places.

I is a bracket bolted to the rear axle G at the longitudinal center thereof, and to it is pivoted the dumping triangular lever J. The 45 upper arm b of this dumping-lever is curved, and its end is loosely attached to the under side of the body A by means of the strap c. The lower arm d of the dumping-lever, which is in an angular position with refer- 50 ence to a vertical line when the body of the wagon is seated on the sills, as shown in Figs. 1 and 2, is strengthened by the braces e.

K is a revoluble shaft underneath the sills D, supported therefrom by hangers f. At one end of this shaft is a spur gear-wheel L, 55 in mesh with a pinion M near the end of a shaft N, which is sustained in hangers g. The end of this shaft is made square to allow of the application thereto of a crank (not shown) which is used in the raising and lowering of 60 the body, as hereinafter described.

O is a chain the upper end of which is attached to the curved portion b of the dumping-bar J by means of a shackle P, and its lower end is wound around and fastened to 65 the shaft K.

Q Q are other chains with their upper ends wound around the shaft K in a reverse direction to the chain O, and their lower ends are fastened to the end of the straight part d of 70 the dumping-lever J by means of a bolt h. (See Fig. 3.)

With the arrangement of chains described it will be seen that when the chains Q are wound the chain O is unwound, and vice 75 versa. Consequently no slackening of any chain can occur in tilting the body, and the body is held firmly in any position in which it may be placed.

To tilt the body A, the shaft N is turned 80 by the crank in the direction indicated by the curved arrow in Fig. 1, which has the effect of winding the chains Q and unwinding the chain O. By continued winding the bar J and the body A attached thereto are brought into 85 the positions shown in Fig. 4. The body is shown in the same position in dotted lines in Fig. 1. A reverse movement of the crank brings the body back to its original position, so that its front end will seat on the sills D. 90

A hinged latch S (shown only in Fig. 6) is hooked over the square portion of the shaft N to hold the body in any position.

In tilting the body as described it will be understood that the rear axle G turns with 95 the body. (See Fig. 4.) This turning of the axle in the dumping operation may be avoided by bolting the springs H to a block T, (shown only in Fig. 7,) which turns about the axle, which is made cylindrical for the 100 purpose.

I claim as my invention—

In a dumping-wagon, the body thereof supported at one end by stationary sills, and at

the other by springs sustained by the rear axle, combined with a dumping-lever hinged to the rear axle or to an attachment thereof, a winding-shaft and winding chains connecting the winding-shaft to the dumping-lever at different sides of the pivotal point, whereby in the revolution of the winding-shaft, one chain is wound while the other is un-

wound, and the position of the lever and its attached body of the wagon changed, substantially as specified.

WILLIAM LEONHARDT.
